(57) **CLAIM**

I claim the ornamental design for a connectable companion computing device, as shown and described.

DESCRIPTION

FIG. 1 is a front, bottom, right perspective view of a connectable companion computing device according to a first embodiment in which the connectors are extended, showing my new design;

FIG. 2 is a rear, bottom, left perspective view thereof;

FIG. 3 is a front elevation view thereof;

FIG. 4 is a rear elevation view thereof;

FIG. 5 is a left elevation view thereof;

FIG. 6 is a right elevation view thereof;

FIG. 7 is a top plan view thereof;

FIG. 8 is a bottom plan view thereof;

FIG. 9 is a front, bottom, right perspective view thereof according to a second embodiment in which the connectors are in a contracted position, showing my new design;

FIG. 10 is a rear, bottom, left perspective view thereof;

FIG. 11 is a front elevation view thereof;

FIG. 12 is a rear elevation view thereof;

FIG. 13 is a left elevation view thereof;

FIG. 14 is a right elevation view thereof;

FIG. 15 is a top plan view thereof;

FIG. 16 is a bottom plan view thereof;

FIG. 17 is a front, bottom, right perspective view thereof according to a third embodiment in which the connectors are extended, showing my new design;

FIG. 18 is a front elevation view thereof;

FIG. 19 is a rear elevation view thereof;

FIG. 20 is a left elevation view thereof;

FIG. 21 is a right elevation view thereof;

FIG. 22 is a top plan view thereof;

FIG. 23 is a bottom plan view thereof;

FIG. 24 is a front, bottom, right perspective view of thereof according to a fourth embodiment in which the connectors are contracted, showing my new design;

FIG. 25 is a front elevation view thereof;

FIG. 26 is a rear elevation view thereof;

FIG. 27 is a left elevation view thereof;

FIG. 28 is a right elevation view thereof;

FIG. 29 is a top plan view thereof; and,

FIG. 30 is a bottom plan view thereof.

(Continued)

Broken lines, showing graphical user interface elements on a display screen and a charging port, represent environmental matter and design portions that form no part of the claimed design.

1 Claim, 26 Drawing Sheets**Related U.S. Application Data**

which is a division of application No. 29/706,209, filed on Sep. 18, 2019, now Pat. No. Des. 918,898.
